DESCRIPTION

FIG. 1 is a perspective view of a collapsible shipping container showing our new design in its erect condition.

FIG. 2 is a perspective view showing the bottom surface; and

FIG. 3 is a perspective view showing the container in its collapsed condition.

The exterior surface opposite that shown on the right in FIG. 1 is identical except that the hinge is raised to effect the collapsing of the opposite sides one over the other as shown in FIG. 3 and the opposite interior surfaces are identical.

FIG. 1

FIG. 2

FIG. 3
